UNITED STATES PATENT OFFICE

ANTHONY L. McCABE, OF NEWTONVILLE, MASSACHUSETTS, ASSIGNOR TO ERIKSON ELECTRIC COMPANY, OF BOSTON, MASSACHUSETTS, A CORPORATION OF MASSACHUSETTS

LIGHTING UNIT

Application filed April 6, 1931. Serial No. 527,861.

The present invention relates to lighting units and more especially to hospital night lights now generally employed as supplementary to the main lighting fixtures for permitting nurses and attendants to perform their night duties in relatively dim light without disturbing the patients by the more brilliant illumination from the main lights, such night lights usually being mounted flush in the wall about 18" above the floor so that the light rays will be below the range of vision of the patient; but certain features of my invention are not limited to such hospital night lights and are capable of more general application.

My invention involves a casing arranged to be mounted in the wall flush with the same, and a front secured to said casing in adjusted and selected angular position with respect to said casing so that said front and the lens or transparent plate carried thereby will always have its lower edge horizontal, notwithstanding any slight inclined position of the casing made necessary by the aperture cut in the wall for receiving the same. My invention involves also a door hinged to the front and a screw passing through said door and having threaded engagement with said front whereby said door may be securely locked in position by turning said screw in one direction, or forced away from said front by turning it in the opposite direction. The door is provided with a rearwardly-extending frame for receiving and supporting a control lens such for example as a refracting plate, or one or more such lenses, or a lens and a diffusion screen, or a lens and a colored glass cover-plate to soften the light, as the case may be, together with means such as screws threaded into the rearward flange of said frame for securing a lens, or any desired combination of lenses and plates, in fixed position in the frame. The lamp support secured to the rear wall of the casing is made adjustable both vertically and radially with respect to its point of attachment to offset the lamp from the focus of the lens and thereby control the direction of the transmitted light.

In the illustrative embodiment of my in-

vention shown in the accompanying drawings

Figure 1 is a front elevation of a lighting unit embodying my invention;

Fig. 2 is a horizontal section taken on the line 2—2 of Fig. 1;

Fig. 3 is a vertical section taken on the line 3—3 of Fig. 1;

Fig. 4 is a fragmentary section on an enlarged scale taken on the same plane as Fig. 3;

Fig. 5 is a fragmentary section on an enlarged scale taken on the same plane as Fig. 2;

Fig. 6 is a fragmentary section taken on the line 6—6 of Fig. 1.

In the particular drawings selected for more fully disclosing my invention, 10 is a casing or wall box of pressed steel or the like, shown in Figs. 2 and 3 as held in a cavity formed in the wall 11. After the last coat of plaster has been put on the wall, the front 12 provided with an opening is mounted on the casing by means which permit a variation in the relative angular positions of the casing and front.

In this particular instance, such means comprise two lugs 13 secured to the base of the casing near the front thereof and two oppositely-disposed lugs 14 secured to the top of the casing. As shown more clearly in Fig. 4, each said lug is provided with an inwardly cupped aperture 15 through which passes a screw 16, the head of which is shown in the present instance as flush with the front and enclosed within a drifted socket 17. A nut 18 having a forwardly-extending ball-shaped portion 19 is threaded to each screw and co-operates with the cup on the lug, these two elements constituting a species of ball and socket joint whereby a substantial angular movement of the front and with respect to the casing may be effected, and said front tightly secured in horizontal position, notwithstanding any inclination of the base of the casing made necessary by the aperture in the wall in which said casing is located.

The door 20 is hinged to the front as shown at 21, 21 to close the opening in said front and is held in closed position by the screw 22.

which passes through, but is not threaded to, said door and is in threaded engagement with the nut 23 secured to the inner face of the front by means of the socket 24. A collar 25 preferably is interposed between the rear face of the door and the front face of the front, said collar being placed on said screw but not threaded thereto. The slight friction between said collar and screw serves to prevent the ready removal of the collar and thereby enables the screw to remain in the door when the latter is open, this being merely a convenient arrangement for preventing the loss of the screw. The door 20 overlies the screws 16 and its ball-and-socket attachments and thereby conceals the same from view.

Secured to the rear face of the door is a frame 26 for receiving and retaining the transparent plates, lenses or the like, employed in connection with the unit. In the present instance I show a prismatic plate or refraction lens 27, and a diffusion screen 28 arranged in said frame. As above stated, it is quite desirable in hospitals to soften the light by means of a colored glass cover plate such as a plate of amber glass. The frame is therefore made sufficiently deep to accommodate one only, or any desired number, of lenses and plates. In order to secure such lens or combination of lenses and plates in fixed position, screws 29, 29 threaded through the rear flange of the frame are employed, such screws pressing against the innermost plate, as shown most clearly in Fig. 2.

In order to vary the direction of light transmission and otherwise control the same, I provide a lamp-supporting bracket 30 which is adjustable vertically and radially with respect to its point of attachment. In the present instance the vertical portion of said bracket is provided with the slot 31 through which passes the screw 32 which is threaded into the rear wall of the casing. By this arrangement the lamp may be raised and lowered with respect to the focus of the lens, or offset with respect to the same by turning the bracket in any given vertical position about said screw as a pivot.

It will be obvious by means of the present invention that the light is utilized by directional control, as distinguished from the methods now in use which involve absorbing louvers or diffusion screens, that the light is accurately directed to the point where it is wanted, and that it is not wasted by cutting it off or absorbing or scattering it promiscuously.

Having thus described an illustrative embodiment of my invention, without however limiting myself thereto, what I claim and desire to secure by Letters Patent is:

1. A lighting unit comprising in combination a casing, a lamp-supporting bracket disposed within said casing, a front for said

casing, lugs secured to the interior of said casing, each of said lugs having a cupped aperture, screws passing through said front and through said apertures, a ball-nut having threaded engagement with each of said screws and taking into the apertures in said lugs, respectively and a door hinged to said front and overlying the heads of said screws. 70

2. A lighting fixture comprising in combination a casing, a lamp-supporting bracket 75 disposed within said casing, a front for said casing, a plurality of ball and socket attachments co-operating with said casing and said front, whereby the relative angular position between said casing and said front may be 80 varied and a door hinged to said front and overlying said attachments.

In testimony whereof, I have hereunto subscribed my name this 4th day of April, 1931.

ANTHONY L. McCABE.
